UNITED STATES PATENT OFFICE.

ELMO W. LEE, OF TAMAROA, ILLINOIS.

DESIGN FOR A CHINA-CABINET.

51,432.

Specification for Design. Patented Oct. 23, 1917.

Application filed July 6, 1917. Serial No. 179,086. Term of patent 7 years.

To all whom it may concern:

Be it known that I, ELMO W. LEE, a citizen of the United States, residing at Tamara, in the county of Perry and State of Illinois, have invented a new, original, and ornamental Design for a China-Cabinet, of which the following is a specification, reference being had to the accompanying drawing, forming part thereof.

The figure is a perspective view of a china cabinet, showing my design.

I claim:

The ornamental design for a china cabinet, as shown.

ELMO W. LEE.

Witnesses:

BESS WOODS,
H. B. HAINES.
